[57] CLAIM

The ornamental design for a beach shoe, as shown.

DESCRIPTION

FIG. 1 is a front view of a beach shoe showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a thirty degree angle of elevation showing view thereof; and,

FIG. 8 is a view of the beach shoe having a foot inserted therein.

The broken line showing of an ankle in FIG. 8 is for illustrative purposes only and forms no part of the claimed design.

1 Claim, 4 Drawing Sheets

FIG 3

FIG. 7
